UNITED STATES PATENT OFFICE.

CHRISTOPHER GROEN, OF ALGONQUIN, ILLINOIS.

DRIVING MECHANISM FOR IRONING MACHINES.

Application filed August 25, 1924. Serial No. 733,939.

This invention relates to a novel driving mechanism for machines including, in combination an element having plural movements of translation, such, for instance as a rotary and an oscillatory movement, together with plural power means operable from a continuously driven rotor to operate the same, and including also a single manual manually operable control means to connect said 5 rotor to the element to operate said element by power derived from said rotor in both its said plural movements, and the invention relates additionally to such mechanism having means to control the power drive to said 10 element in a manner to arrest one of said movements during continuance of its other movement.

My improvements are shown as adapted to operate the roll of an ironing machine of 20 that type in which the work to be ironed is pressed between a rotatable padded roll and the concave face of a heating shoe, the work being drawn therebetween by the tractive effort of said roll whose upper feed face 25 moves towards the receiving side of said shoe. Said roll is carried by swinging arms and is pressure held towards the shoe by power applied through said arms. The roll driving mechanism is so constructed and controlled as to readily connect power to and 30 disconnect it from the roll, and to also apply roll pressure to and relieve it from the work, so that the roll is under constant control to be rotated to perform its ironing functions, 35 and to be released from and pressed towards the shoe by oscillating motion of its swinging support to facilitate adjustment of the work between the roll and shoe.

Among the objects of the invention, as applied to such an ironing machine, is to produce a roll driving and roll pressure mechanism which can be operated from a continuously rotatable shaft or rotor, and to be 40 at all times under the ready and perfect control of the operator for adjusting the work in the machine for connecting power to drive the roll and for quickly releasing and applying ironing pressure, all separately and sequentially operative through power derived 45 from the prime rotor.

A further object of the invention is to produce in a mechanism of this general character for imparting independent movements to an element (such, for instance as a rotary 50 and a lateral movement), a control which is arranged to be manually set in operation,

and is constructed to complete its operation to sequentially give independent movements to said element and to disconnect said mechanism from power derived from a continuously driven rotor. 60

A further object of the invention is to produce, in a driving gear mechanism, including a normally continuously driven element or rotor and an intermittently driven element, novel power means, under initial manual control, to automatically connect by power means driving power to and to likewise disconnect driving power from the intermittently driven element. 65

Another object of the invention is to produce a driving mechanism for an ironing machine of the general character shown, so constructed and adapted that the rotating and laterally movable element (the ironing roll) is so connected and disconnected to power that said roll is connected to power and is rotating just before the roll pressure is applied to the shoe and, as a separate improvement, to cut off driving power from the roll just after the roll pressure is released so that thereby after such pressure release, the roll is free to rotate. 70

A further object of the invention is to provide a quick release mechanism, operable by hand or foot power to quickly release the rotatable element from a stationary element in the event power energy is cut off from the machine, as for instance if the feed circuit of an operating motor be opened. 75

A further object of the invention is to produce a novel, manually tripped, power operated toggle connection for the pressing roll or analogous pressing element, constructed to maintain the roll or element yieldingly pressed against an abutment and to automatically and quickly apply and release said pressure. 80

Other objects of the invention are to otherwise improve, simplify and render positive driving and controlling mechanism of this general character, and the invention consists in the elements and combination of elements shown in the drawings and described in the specification, and is pointed out in the appended claims. 95

While my invention as herein shown is adapted to an ironing machine of the roll and shoe type, it will be understood that it is capable of adaptation to other machines where driving and control functions of the character herein set forth are desirable. 100

As shown in the drawings:

Figure 1 is a front elevation of an ironing machine equipped with my improvements.

5 Figure 2 is an end view thereof.

Figure 3 is a detail section on the line 3-3 of Figure 2, with parts omitted.

Figure 4 is an enlarged horizontal view, with parts broken away, on the line 4-4 of

10 Figure 5.

Figure 5 is a part elevation and part section on the line 5-5 of Figure 4, as viewed from the direction indicated by the arrows.

Figure 6 is a vertical section on the line 15 6-6 of Figure 4.

Figure 6^a is a detail section on the line 6^a-6^a of Figure 1.

Figure 7 is a detail vertical section on the line 20 7-7 of Figure 4, looking in the direction indicated by the arrows.

Figure 8 is a vertical section on the line 8-8 of Figure 4, looking in the direction indicated by the arrows.

Figure 9 is a detail front elevation at the 25 right hand side of the machine, illustrating a portion of a carrying arm for the roll, and the driving clutch and its accessories.

Figure 10 is an end elevation of the parts shown in Figure 9.

30 Figures 11 and 12 illustrate detached parts of the rocking cam and accessories shown in Figure 8, but in changed positions.

Figure 13 is a detail section on the line 13-13 of Figure 6.

35 Figures 14 and 15 are detail elevations, with parts in sections, illustrating two positions of a dog and its control which connects and disconnects power to and from the intermittently operative shaft of the driving 40 mechanism.

Figure 16 is a perspective view of the parts illustrated in Figures 14 and 15.

The end frames 17 of the base of the ironing machine are connected by a back 45 plate and also by tie elements 18, and the upper frame part of the machine comprises two end members 19 having rear upstanding standards 20 to support the ironing shoe 21 which extends from end to end of the 50 machine and has a forwardly facing concave ironing face.

The hollow ironing roll 22 is rotatably supported, through a central sleeve 23, on a fixed horizontal shaft 24 that is carried 55 by the upper ends of swinging arms 25 which are pivoted at their lower ends to swing in vertical planes. Said shaft is fixed to the upper ends of said arms by set screws 26 extending obliquely through inward extensions or hubs 27 of said arms to impinge against said shaft 24 so as to cause the roll to be moved toward and away from the concave face of the shoe when the arms are 60 swung on their pivots, in the manner hereinafter described. The roll is hollow at its

ends, and there is fixed to said sleeve 23 an annular ring fitted tightly in said hollow end and formed as an internal gear 28 that meshes with a pinion 29 fast on a short shaft 30 that is rotatively mounted in said 70 inward extension or hub 27 of the roll supporting and pressure arm 25 and at its outer end carrying a gear 31 constituting the upper terminal gear of a driving train, herein-after to be described, enclosed in the hollow 75 or chambered arm 25.

34 designates a feed board over which the work is fed onto the roll and into the space between it and the ironing shoe, and the frame of said board is supported by pivots 80 35 and upholding springs 36, which latter are sustained on said arms. Normally the feed board is disposed in a plane substantially tangent to that of the upper face of the roll. Said board affords means to support the work preparatory to introducing it between the roll and shoe, and its pivotal function about its pivots 35, against the action of the restoring springs 36, enables it to actuate the control for the roll driving 90 and roll oscillating mechanisms in the manner hereinafter described.

The roll is driven through a train of transmission or driving gears 38, the shafts of which are mounted in the walls of one 95 of the hollow arms, in accordance with the invention set forth in Patent 1,580,195, granted April 13, 1926, to Herman G. Grosse. The upper terminal gear 31 carries the stud 30 before referred to, and the lower gear of the train is driven by a gear 59, hereinafter described, in a manner to permit the said arm enclosing the gear train to pivot about the axis of the driving gear and to remain in driving mesh therewith at 100 all times. The lower ends of said pressure arms 25 terminate in hubs 40, 40', both of which are circumferentially faced to rockingly engage internally cylindric bearings in the end frame pieces 19. The supporting 110 and pressure arm hub 40, at the lower end of the right hand arm is internally mounted on a bushing 43 that is supported on a rotatable countershaft 45 which rotates in said bushing 43 and a bushing 46 which is supported in a casing 47 that encloses the principal parts of the driving gear mechanism, as best shown in Figures 4 and 6, and is rigid with the frame.

Said countershaft 45 is driven through a 120 driving shaft 50 that is belted to a motor 51 that is wall mounted on the frame, the driving connections including a worm 52 on the countershaft and a worm gear 53 that is keyed to said countershaft. On the outer 125 end of the countershaft 45 is a sleeve 54 that is threaded at its outer end to the reduced outer end of said shaft, the hand of the screw relatively to the direction of rotation of the shaft 45 being such as to normally hold the 130

sleeve against a shoulder on the shaft at its reduced, screwthreaded portion. Slidable on said sleeve 54 and splined thereto is a clutch collar 56, having on its inner end an annular series of clutch teeth 57 adapted to mesh with an annular series of clutch teeth 58 formed on the outer face of the gear 59 that meshes with the lower terminal gear 38 of the driving gear train hereinbefore referred to. When the clutch, thus produced is mated, the driving gear train and the roll is rotated by the motor 51; and driving power is disconnected at said clutch by endwise outward movement of the sleeve 56. The clutch 15 collar is shifted on the sleeve 54 through the axial movement of a rotative shaft 60 having rotative and axial bearing in the end frame plate 19 and casing 47, said shaft having at one end beyond said frame plate a forked 20 shifter finger 61 which engages in an annular groove of said clutch collar. Said shifter finger 61 is loose on the shaft 60, permitting the latter to rotate therein, and it is confined between a shoulder on said shaft and spring 25 64 that is interposed between one side of the finger and an opposing face in a knob 65 that is threaded to said shaft in the manner shown in Figure 6. Said spring 64 affords a loose or yielding connection between the 30 clutch teeth 57, 58 to permit them to go into mesh without clashing, both when the clutch collar 56 is operated by hand through the knob 65 and when the clutch is operated by power.

35 The said shaft 60 is axially shiftable by power to control the clutch collar 56, and thereby connect the roll to and disconnect it from driving power, by means of a cam, designated as a whole by 80 (Figure 13). Its beveled edge engages a grooved collar 80' fast on the shaft 60, and the lateral offset of the rotating cam, when rotating with the shaft 45, gives axial shifting movement to the clutch actuating shaft.

40 Said cam is herein shown as made integral with an eccentric body 66 which is normally loose on the shaft, but can be locked thereto by a dog and ratchet mechanism, under the control of a rocking cam 91, shown and hereininafter to be described. The eccentric body is held from movement along the shaft 45 between the hub of the worm gear and a collar 67 keyed to the shaft 45.

45 The construction described provides means for transmitting driving power at a suitable speed from the motor 51 to the roll 22 through the train of gears in the hollow right hand supporting and pressure arm 25. The roll 22 can thus be rotated through the 50 shaft 45, the sleeve 54 and the clutch element on the clutch collar 56 and gear 59 throughout any desired duration, and during such rotation of the roll it is pressure-held towards the shoe. When the roll is thus being 55 turned the shaft 45 rotates freely in the ec-

centric body 66 and the rocking cam 91 and transmits no movement to the latter. Said eccentric body is adapted, however, to be locked to the shaft 45 by a dog and ratchet mechanism, under the control of the rocking cam 91, in a manner hereinafter to be described, to swing the roll supporting and pressure arms 25 to press the roll toward and to release it from the shoe. During the release of the roll pressure from the shoe, the clutch mechanism is actuated to disconnect driving power from the roll, and when the roll is pressed towards said shoe the clutch is actuated to connect driving power to the roll.

80 The detail of the present embodiment of the structure for connecting power to and disconnecting power from the roll, and for operating the roll pressure and release means is made as follows:

85 68 designates an eccentric strap which encircles said eccentric body 66. It is connected to the front end of a rearwardly extending link 69 (Figures 4 and 5) that is pivoted at its rear end by a pin 69' to a crank arm 90 70 of a rock shaft 67' which extends from end to end of the machine frame and is mounted to rock in bearings 19' in the upright members 20 of the frame members 19. At the ends of the machine, just inside of the 75 end frame members 19 are rearwardly extending vertically swinging crank arms 71, the forward ends of which are apertured to fit over the hubs 40 of the roll supporting and pressure arms and are fixed thereto by 80 keys backed by locking screws 71'. The rear ends of said crank arms 71 are connected by yielding toggle connections to said rock shaft 67', the construction being such that when said shaft is rocked on its axis the 85 crank arms 71 are actuated to swing the roll supporting and pressure arms towards and from the ironing shoe once during each rotation of the eccentric body 66. The yielding function of the connection serves to resiliently press the roll toward the shoe.

90 Said yielding toggle connections comprise, in combination with crank arms 72 fixed to the shaft 67', pairs of telescopic members 73, 74, respectively, pivoted at 75, 76 to said 95 rock shaft crank arms 72 and to the rear ends of the crank arms 71, respectively, said element 73 being hollow to receive the element 74; and between a shoulder on the element 73 and a shoulder on the element 100 74, and surrounding the latter elements, is interposed a spiral compression spring 77, the compression function of which is to yieldingly press the roll against or towards the shoe. A head 74' on the toggle element 74 105 engages an internal shoulder in the toggle element 73 to limit the endwise expansion of the toggle device.

110 The parts are shown in Figure 5 in the 115 positions which they occupy when the roll 120 125

is retracted from the shoe and driving power is therefore cut off from the roll. At this time it will be noted by an inspection of said Figure 5 that the longer radius of the eccentric cam body 66 is between its rotating axis and the pivot pin 69'. Therefore the arms 71 occupy their upward positions and, by reason of their interlocking connection to the hubs 40 of said arms through the keys and screws 71', the roll supporting and pressure arms are swung outwardly. The dash straight and curved lines on Figure 5 indicate the positions of the arm 71, link 69 and the crank arms 70 and 72 and the resilient toggle connection between the crank arm 71 and the rock shaft 67', which said parts occupy when the roll is being held up against the shoe.

Referring now to the means for connecting and disconnecting the continuously rotative shaft or rotor from the roll driving means and for connecting and disconnecting said shaft or rotor to and from the roll pressure and pressure release means, the same is made as follows:

82 designates a rock shaft which extends loosely through and has rocking motion in an opening in the eccentric body 66; said shaft and opening being parallel, and out of line, with the center of said eccentric body and on the side of the longer radius of said body from the shaft 45. 83 designates a dog which is carried by one end of said rock shaft 82. Said dog is disposed between said cam 80 and the ratchet wheel 84 which is fast on the worm gear 53, surrounding the hub of said worm gear (Figure 4). The shank of said dog is parallel to the face of said ratchet wheel and its tooth 85 is laterally offset to engage the peripheral teeth of said ratchet wheel, as indicated in Figures 7, 13 and 16. This arrangement affords compact disposition of the parts along the axis of the shaft 45 and enables the dog to be made rugged relatively to the space occupied thereby. The said dog 83 has a small angular lost motion connection to the shaft 82, as by means of a stud 86 threaded through the hub of the dog and engaging at its inner end a peripheral notch or recess 87 in the shaft (Figures 14 and 15). 85' designates a leaf spring which is supported by a clamp 80' carried by the cam 80, the free end of said spring bearing against the toothed ends of the dog in a manner tending to press the free end of the dog towards the ratchet and to permit the dog to yieldingly back away from the ratchet for purposes hereinafter to be described.

60 Non-rotatably fixed to the end of the shaft 82 remote from the dog is a dog-controlling arm 82'. Rigid with the free end of said arm is a cam stud or roll 82'' that travels in a peculiarly shaped cam track formed principally between the outer and inner dia-

metrically disposed concentric walls 89, 90 of the before-mentioned rocking cam 91 mounted for limited rocking movement on the shaft 45. It is held from movement endwise along said shaft between the collar 67, 70 before mentioned, and the hub 40 of the right hand roll supporting and pressure arm (Figures 4 and 6). The track of said cam is disposed as two diametrically opposite concentric portions 88, 88 and as two shorter 75 diametrically opposite, eccentric portions 88', 88'.

The outer wall of said track 88 is not continuous, but is interrupted or open at points disposed diametrically across the axis of the 80 cam. Said openings in the outer cam walls are bridged by the leaf springs 92 that are fastened to the free ends of the concentric parts of said outer wall. Each spring is directed obliquely inwardly across its associated wall opening and slightly overlaps the associated eccentric lip 93 of the outer wall and the corresponding eccentric inner wall 94 formed on the perimeter of the inner solid cam part or body. 90

96, 96 designate pins or abutments fixed to the cam 91. They are disposed transversely of said springs to bear on the outer faces thereof in such a way that the free ends of said springs may be sprung outwardly by the cam lug or roll 82' when the latter is moved along and inside said springs, and to thus tend to rock said cam on its axis in one direction against the action of a cam restoring spring, to be hereinafter described. 100

Said rocking cam 91 is provided with diametrically disposed radial arms 98, 99. The rear arm 98 extends backwardly through a slot 100 in the casing 47 and vibrates between limiting shoulders at the ends of said slot. Said arm 98 is normally pulled downwardly by a tensile spring 101 fixed to said arm and anchored to a pin fast on said casing 47, as shown in Figures 5, 8 and 10. The front arm 99 likewise extends forwardly through a slot 102 in the casing wall to vibrate between limiting shoulders at the ends thereof. 105

103 designates a latch arm that is located in front of casing 47 and is fast on a rock shaft 104 which is rockingly supported in bearings in the machine frame. The upper end of the latch has a down-turned hook 105 which lies in the path of a laterally directed lug or pin 106 fixed to the end of said arm 99 and is adapted in certain parts of the operating cycle to engage over said pin to hold the rocking cam 91 stationary against the action of the spring 101. When the cam 91 is thus held, it is normally stationary to permit the cam lug or roll 82'' to travel through the cam slot thereof. A spring 108 unitarily assembled with the latch 103, in rear thereof, bears against the 110

casing 47 to normally hold the upper hook end 105 of the latch swung forwardly to the position indicated in full lines in Figure 8 and in dotted lines in Figure 10, to be in 5 the path of the pin 106, when the cam 91 is rocked to the position shown in dotted lines in Figure 11, and to be thereby in position to engage said pin 106 and to limit the restoring movement of said rocking cam under the action of the spring 101. The forward swing of the upper end of said latch is limited by an adjustable screw or abutment 110 which bears against said casing 47 below the shaft 104. 10 15 The latch is tripped from the pin 106 through the medium of a plunger 112 that is loosely connected at its upper end to the swinging feed board frame and is adapted to engage at its lower end the rear end of a 20 crank arm 113 that is fast to and extends rearwardly from the rock shaft 104. When said latch is so tripped, the spring 101 rocks the cam 91 in a clockwise direction, as shown in Figure 12, the rocking movement of said 25 cam being limited by engagement of the arm 98 with a shoulder 114 at the lower end of the slot 100, as shown in said Figure 12.

Operation.

30 When the parts are in the positions indicated in Figure 2, the roll 22 is closed on the shoe and at this time the gear train clutch is closed and driving power is transmitted through the shaft 45 to the roll driving gear train. Said shaft 45 is also rotating freely through the eccentric body 66 and the dog 83 is free from the ratchet 84. In the principal figures of the drawings, the mechanism is in its open position, or in the 35 position in which the roll 22 is released from the ironing shoe and the shoe is disconnected from power to rotate it.

It may be stated here that when the cam roll 82² is occupying an eccentric portion of 40 the track, at either side of the axis of rotation of the eccentric body 66, the dog 83 is disengaged from the ratchet wheel 84 because the said roll is shifted away from said axis and the tooth of said dog is shifted or 45 raised away from said ratchet, so that no power will be transmitted from said ratchet to said eccentric body. So also when the cam roll 82² is occupying a concentric position at either side of the axis of rotation of 50 said eccentric body, the tooth of said dog 83 lies against and engages the ratchet to transmit power from the ratchet to said eccentric body. In either the open or closed positions 55 of the parts, the rocking cam is locked stationary by its latch 103, as shown in Figure 8, against the action of the spring 101.

Assuming the machine to be open, tilting depression of the feed board 34 acts through 60 the plunger 112 and rock arm 113 to release 65 the latch from the cam arm 99, whereupon

the spring 101 rocks the cam 91 in a clockwise direction and forces the adjacent concentric part 88 of the cam track over the cam roll 82². The rocking movement of the cam is limited by engagement of the arm 98 70 with the shoulder 114. This movement of the roll towards the axis of the cam 91 acts through the arm 82' to turn the rock shaft 82 in a clockwise direction and to force the tooth of the dog 83 towards and against the 75 ratchet wheel 84. Therefore, the eccentric body is temporarily locked to rotate with the shaft 45 and power is transmitted from the shaft 45 through the eccentric strap 68 and link 69 to rock the shaft 67' and thereby 80 lower the rear ends of the crank arms 71 to swing the arms 25 rearwardly and thereby force the pressing roll 22 towards the shoe. Such rotation of the eccentric body also carries the cam roll through the concentric part 88 of the cam or from the position shown in full lines to that shown in dotted lines in Figure 12. The yielding toggle between the shaft 67' and the arm 71 85 serves to firmly hold the roll 22 pressed towards the shoe until the eccentric body is again connected to the shaft or rotor, which occurs after a next succeeding tripping of the rocking cam 91.

The clutch shifting cam 80 at the same 90 time is acting on the shaft 60 to shift it endwise to close the gear train clutch (57, 58) and the movement of the parts are so timed that the pressing roll, theretofore disconnected from the driving shaft or rotor 100 45, will be in rotation just before it is brought to pressure position against the work. This is a desirable feature because the work is at once, upon applied pressure, caused to pass between the roll and shoe. 105

The cam roll 82², after its travel through the concentric part of the cam track, is brought into engagement with the rising side of the inner wall of the next onward eccentric cam track portion 88' (see Figure 110 12), and forces the free end of the adjacent spring 92 outwardly, curving it about the pin 92, as shown in Figure 11. The friction generated between said roll and the inner face of the cam track on one side and the spring on the other side, overcomes the tension of the rocking cam restoring spring 101 and rocks said cam 91 in a counter clockwise direction and swings the pin 106 of arm 99 past the hook of the latch 103. During 115 this rocking movement of the cam 91 and before it has reached the limit of its throw, the cam roll 82² passes the end of the spring 92, but has not passed fully into the next eccentric portion 88' of the cam track. It is at this time that the rock shaft 82 is rocked sufficiently to release the tooth of the dog 83 from the ratchet 84 to thereby 120 disconnect the shaft or rotor from the pressure releasing means for the roll 22. After 125 130

the release of the cam roll 82² from the spring 92, the spring 101 acts to rotate the cam 91 in a clockwise direction to permit said cam roll to pass fully into the eccentric portion 88' of the cam track, which will further swing the tooth of the dog 83 from the ratchet 84. The cam restoring movement will be arrested by engagement of the pin 106 with the latch hook 105. Thereafter, and until the latch 103 is again tripped, the cam roll will remain in the eccentric part of the track of the rocking cam 91 and the shaft or rotor 45 will rotate freely in the eccentric body and will continue to drive the pressing roll against the work (see dotted line of cam 91 in Figure 11).

When it is desired to release the pressing roll from the shoe and to disconnect power from the gear train, manual pressure is applied to tilt the feed board 34 and thereby release the latch 103 from the arm 99 of the rocking cam 91, in the manner shown in Figure 11, and at a time when said cam roll 82² is occupying a position in the eccentric part 88' of the cam track diametrically opposite to that shown in Figure 8. The spring 101, acting on the arm 98, will thereupon swing said arm downwardly and cause the cam 91 to rock in a clockwise direction until the parts are arrested by the limiting shoulder 114, or a correlative shoulder in the slot 102, as desired. This movement of the rocking cam shifts the next forward concentric part of the cam track over said cam roll, or a position just in advance of the dotted line position of the rocking cam shown in Figure 11. Thereby said cam roll 82² is swung inwardly to rock the shaft 82 in a clockwise direction to cause the dog to engage the ratchet wheel 84 and thus rotate the eccentric body in a direction to release the pressing roll from the ironing shoe. The cam 80 also rotates with the eccentric body and its operation is in a direction to demesh the gear train clutch. The operation of said clutch occurs just after the pressing roll pressure is released, thus permitting the said roll to be turned freely by hand. During this time, the rocking cam remains in the position shown in Figure 12, and the cam roll is passing through a concentric portion of the cam track to maintain driving connection between the ratchet 84 and the cam body 66. This driving connection continues until engagement of the cam roll 82² with the next succeeding pin-backed spring 92 rocks the cam 91 in a counter clockwise direction against the action of the spring 101. The dog is then disconnected from the ratchet wheel 84 at a time when the cam roll is climbing the rising side of the eccentric cam track part and just as the roll passes away from said spring 92. The spring 101 thereupon restores the rocking cam and shifts its eccentric part over

the cam roll, the position indicated by dotted lines in Figure 11. The clutch controlling cam 80 has in the meantime been operating to shift the shaft 60 outwardly and thereby open the clutch (57-58) to disconnect said shaft 45 from the roll driving gear train. 70

It will thus be seen that the pressing roll can be yieldingly pressed towards and released from the shoe once during each complete rotation of the countershaft 45 and 75 that the roll may be held pressed against the shoe and rotated an indefinite number of turns, depending upon the length of work being ironed. The roll is rotated comparatively slowly, relatively to the speed of the 80 shaft 45 which drives the same, due to the gear ratio between the pinion 29 and internal gear 28. It will also be observed that the control for the roll driving and pressure and release mechanism can be manipulated by 85 the same swinging movement of a single element and without change of the operator from a central operating position. It will also be observed, so far as is concerned the operation as thus far described, that said 90 control mechanism is wholly power operated, after the initial manual operation of a single trip.

In the event the motor circuit should be opened at a time when roll pressure is applied, and therefore power to the countershaft 45 be cut off, manual means are provided for quickly releasing the roll pressure and thus prevent scorching the work. This can be effected by providing the shaft 60 100 with an elongated toothed pinion 116 to mesh with a plate gear 117 made fast to the eccentric body 66 on the side thereon remote from the cam 80. This shaft can be rotated by hand power applied to the knob 65 to turn 105 the shaft 45 in the same direction as it is designed to be turned by power, whereby said eccentric body acts on the link 69 to break down the yielding toggle connection to the roll, and to permit the roll pressure 110 to be released; and the cam also acts on the shaft 60 to break the clutch connection to the roll driving gear train. It is only necessary to withdraw the pressure roll slightly 115 from the shoe in order to release the work and if full cycle of movement be not effected, it will be continued by power when the motor circuit is again closed. The lost motion between the dog 83 and the shaft 82 permits the dog to yield against the spring 85' 120 and click over the ratchet wheel 84, which at this time is not turning.

I claim as my invention:

1. In an ironing machine, a shoe and a rotatable roll, a movable feed board adjacent to 125 the roll, mechanism for effecting relative bodily movements between the shoe and the roll, mechanism for rotating the roll, and means controlled by movements of said feed board for setting said mechanisms into operation. 130

2. In an ironing machine, a shoe and a rotatable roll movable bodily relatively to each other, a feed board adjacent to said roll and capable of moving independently of the 5 shoe and roll, and means controlled by said feed board for rotating the roll and producing relative bodily movements between the roll and the shoe.
3. In an ironing machine, a stationary 10 shoe, a roll mounted so as to be rotatable and also bodily movable from and toward the shoe, a feed board mounted adjacent to the roll so as to partake of the bodily movements of the latter and capable of limited 15 movements independently of the roll, and means controlled by the said independent movements of the feed board for rotating the roll and moving it from and toward the shoe.
4. In an ironing machine, a shoe and a roll, a feed board mounted adjacent to the roll and capable of movements independent of the shoe and the roll, and means controlled by such independent movements of 20 the feed board for producing relative bodily movements of the shoe and the roll from and toward each other.
5. In an ironing machine, a stationary shoe, a rotatable roll, a swinging support for 25 the roll, a feed board hinged to said support adjacent to the roll, a spring yieldingly holding said board raised and permitting it to be depressed, and means controlled by a tilting movement of the feed board to rotate 30 the roll and swing said support to carry the roll from and toward the shoe.
6. In an ironing machine, a stationary shoe, a rotatable roll, a swinging support for 35 said roll, a feed board yieldingly mounted on said support adjacent to said roll so as to be capable of being depressed, mechanism including clutch means for rotating said roll and swinging said support, a clutch actuator including a tripping device, and a part connected to said feed board and adapted to 40 operate said tripping device when the feed board is depressed.
7. In an ironing machine, two elements one of which is capable of bodily movements 45 relatively to the other and one of said elements being rotatable, an independently movable feed board mounted adjacent to one of said elements, a continuously rotat- 50 ing driving member, a power transmitting means between said driving member and the rotatable element to impart rotary move- 55 ment to the latter, a second power transmitting means between said driving member and one of said elements to impart bodily 60 movement thereto relative to the other element, and means controlled by movements of said feed board to cause both of said power transmitting means to be connected to and disconnected from said driving mem- 65 ber.
8. In an ironing machine, a shoe and a rotatable roll, a power device, separate power transmitting mechanisms to impart a rotary movement to said roll and relative bodily 70 movements between the shoe and the roll, a feed board mounted adjacent to said roll and capable of limited movement independently of the shoe and the roll, and means controlled by said feed board to cause said 75 mechanisms to be connected to and disconnected from said power device.
9. In an ironing machine, a stationary shoe, a rotatable roll, a swinging support for said roll, a feed board mounted on said 80 support adjacent to said roll and having capacity for limited movements relative on the support, a power device, separate power transmitting mechanisms to impart a rotary movement to the roll and swinging move- 85 ments to said support, and means controlled by said feed board to cause said mechanisms to be connected to and disconnected from said power device.
10. In an ironing machine, a shoe mem- 90 ber and a rotatable roll member, a movable support for one of said members to permit relative bodily movements between said members, a feed board mounted adjacent to said roll member and capable of limited 95 movements independently of both of said members, a power device, separate power transmitting mechanisms to impart a rotary movement to said roll member and move- 100 ments to said support to cause bodily relative movements between said members, and means controlled by said feed board to cause said mechanisms to be connected to and disconnected from said power device.
11. In combination, an element capable 105 of two independent motions, a continuously driven rotor, an eccentric loose on said rotor and connected to said element to impart one of said motions thereto, a driving connection including a clutch between said rotor and said element to impart thereto the other of said motions, means rotatable with the eccentric to operate the aforesaid clutch, a second clutch between the eccentric and the rotor, and manually controlled means to operate said second clutch.
12. In combination, an element capable 115 of two independent motions, a continuously driven rotor, an eccentric loose on the rotor and connected to said element to impart one of said motions thereto, a driving connection including a clutch between said rotor and said element to impart thereto the other of said motions, means rotatable with said eccentric to operate said clutch, a dog and ratchet mechanism between the rotor and 120 said eccentric, and a single manual controller having means to connect and disconnect the dog and ratchet mechanism.
13. In combination, an element capable 125 of two independent motions, a continuously 130

driven shaft, an eccentric loose on said shaft and connected to said element to impart thereto one of said motions, a driving connection including a clutch between said shaft and said element to impart the other of said motions thereto, means rotatable with the eccentric for operating the aforesaid clutch, a second clutch between said eccentric and said shaft, means including a rocking member loose on the shaft for operating said second clutch, and a manual controller for said rocking member.

14. In combination, an element capable of two independent motions, a continuously driven shaft, an eccentric loose on the shaft and connected to said element to impart thereto one of said motions, a driving connection including a clutch between said shaft and said element to impart the other of said motions thereto, a ratchet wheel fixed to the shaft, a dog on said eccentric, a rocker device loosely mounted on said shaft and engaged with said dog to move it into and out of engagement with said ratchet wheel, and a manual controller for said rocker device.

15. In an ironing machine, a shoe and a rotatable roll, a movable feed board adjacent to the roll, mechanism for alternately bringing the shoe and the roll together and separating them, a second mechanism for rotating the roll, and means controlled by a movement of the feed board for setting said mechanisms in operation to bring the shoe and roll together and rotate the roll and operated by a succeeding like movement of the feed board to separate the shoe and roll and stop the rotation of the roll.

16. In an ironing machine, a shoe, a rotatable roll, a movable feed board adjacent to the roll, operating mechanism for producing relative bodily movements between said roll and said shoe, operating mechanism for rotating said roll, controlling mechanisms set in action by a movement of the feed board to cause the roll to rotate and be brought near the shoe and to be set in action by a succeeding similar movement of the feed board to separate the shoe and the roll and stop the rotary movement of the roll.

17. In an ironing machine, a shoe and a rotatable roll, a movable feed board, a driving gearing for rotating the roll, means including an eccentric for producing relative

bodily movements between the shoe and the roll, a power device, and means controlled by said feed board to connect said driving gearing and said eccentric to said power device and the eccentric to be turned through one half of a revolution when the feed board is given a predetermined movement and to disconnect the driving gearing from the power device and connect the eccentric to the power device to cause the eccentric to turn through the other half of said revolution when the board is given a second similar predetermined movement.

18. In combination, an element mounted for bodily and rotary movements, a continuously driven shaft, an eccentric loose on the shaft, a connection between the eccentric and said element to impart bodily movements to the latter, a driving connection including a clutch between said shaft and said element to impart rotary movement to the latter, an actuator for the aforesaid clutch including a cam on the eccentric, a second clutch for connecting the eccentric to said shaft, a rocking cam, a spring connected to the rocking cam for rocking it in one direction, an actuator for said second clutch including a member mounted on the eccentric, a cam roll on said member engaged with said rocking cam to be moved thereby and to move the same in the direction opposite that in which it is moved by the spring, and a catch for said rocking cam.

19. In combination, an element mounted for bodily and rotary movements, a continuously driven shaft, an eccentric loose on said shaft and connected to said element to produce bodily movements thereof, a clutch between the eccentric and the shaft, driving means including a second clutch between said shaft and said element for rotating the latter, a cam fixed to said eccentric for throwing in said second clutch when the eccentric is in one angular position and for throwing out the clutch when the eccentric is in a second angular position, and manually controlled means for operating the clutch between the eccentric and the shaft.

In witness whereof I claim the foregoing as my invention, I hereunto append my signature this 8 day of July, 1924.

CHRISTOPHER GROEN.
